UNITED STATES PATENT OFFICE.

JAMES A. CARLTON, OF NEWARK, NEW JERSEY.

PAPER JOGGER.

Application filed January 16, 1925. Serial No. 2,766.

To all whom it may concern:

Be it known that I, JAMES A. CARLTON, a citizen of the United States, and a resident of Newark, in the county of Essex and State of New Jersey, have invented new and useful Improvements in Paper Joggers, of which the following is a specification.

This invention relates to a device commonly known as a paper jogger for evenly 10 stacking or piling sheets of paper or the like as they are discharged from a machine, for example, a multigraph printing machine.

Paper joggers are well-known in the printing press art, and are usually large, 15 complicated and expensive devices, which apparently accounts for the failure of or relatively slow adoption of similar devices for multigraph and other small printing machines.

Accordingly one object of my invention is to provide a paper jogger embodying novel and improved features of construction which is particularly adapted for use with multigraph and other similar printing machines, 25 although the invention is not limited to such use.

Another object is to provide a device of the character described which can be easily and quickly applied to an ordinary multigraph machine without structural modification thereof.

Further objects are to provide a novel and improved paper jogger which can be easily and quickly adjusted to accommodate paper of different widths; to provide such a device embodying a small number of simple and inexpensive parts, and to obtain other results and advantages as may be brought out by the following description.

In the accompanying drawing I have shown a paper jogger particularly designed for use in connection with known multigraph machines, but it will be understood that this is mainly for the purpose of illustrating the principles of the invention and that the device is susceptible of use with other machines and the details of construction can be varied without departing from the spirit or scope of the invention.

Referring to said drawing in which the same characters of reference designate corresponding and like parts throughout the several views.

Figure 1 is a side elevation of a paper jogger applied to a known type of multi-

graph machine, the machine being fragmentarily shown;

Figure 2 is a transverse vertical sectional view taken on the line 2—2 of Figure 1, and

Figure 3 is an enlarged perspective view of the jogger.

Specifically describing the present embodiment of the invention, the reference character A designates a table to receive 65 sheets of paper as they are discharged from a multigraph machine B, said table being of the known construction and including two vertical sideboards C and D one or both of which are adjustable toward and from 70 each other transversely of the table A to accommodate paper of different widths.

It will be understood that the sheets of paper are automatically discharged from the machine B and that the sideboards C 75 and D are so positioned on the table A and relatively to each other as to receive the sheets of paper between them as shown in Figures 1 and 2 of the drawings. A wire frame E is supported from the machine B 80 over the table A to prevent the papers from flying outwardly over the tops of the sideboards C and D and another wire frame F is arranged at the outer end of the table A 85 to prevent papers from sliding endwise from the table.

In accordance with the invention, one of the sideboards, in the present instance the board C, is freely movable toward and from the other board D, and said board C is normally spaced from the board D a distance 90 which provides a small space between said board C and the edge of a sheet of paper which has its other edge bearing against the board D, as clearly shown in Figure 2. 95 The papers as they are discharged from the machine fall upon the stack G more or less irregularly, as indicated by the top sheet of the stack in Figure 2, and the board C is periodically and synchronously with the discharge of the papers from the machine B, moved toward the stack so as to push the irregularly discharged sheets against the board D, as shown in Figure 2, so that the sheets of paper are arranged in a stack having even edges.

The jogger includes a body portion 1 which is preferably formed of cast metal and is provided at one end with lugs 2 formed with openings 3 to receive fastening 110

members such as screws 4, said lugs 2 being secured to the underside of the table A by means of the screws 4, as shown in Figure 2.

The body portion 1 is also formed with a pair of spaced upwardly projecting bearing posts 5 in which is slidably mounted a rod 6 carrying at one end a plate 7 having a plurality of openings 8 to receive screws for securing the plate 7 to the movable sideboard C. A tension spring 9 has one end connected to the plate 7 as at 10, and the other end connected to a stud 11 mounted on a vertical flange 12 of the body portion 1, said spring tending to draw the plate 7 toward the body portion 1 until the plate abuts the outer bearing post 5, as shown in Figure 3. A sleeve 13 is adjustably mounted on the rod 6 between the bearing posts 5, said sleeve carrying a set screw 14 whereby the sleeve may be fixedly secured to the rod 6 at various positions.

A bell-crank lever 15 is pivotally mounted on the body portion 1 by a pivot bolt 16, and one arm of said lever is bifurcated or forked as at 17 to embrace the rod 6 at the rear of the sleeve 13, as clearly shown in Figure 3. The other arm of the bell-crank lever is provided with a transverse opening 18 in which is slidably arranged a rod 20 which has one end connected as at 21 to a crank arm 22 on a shaft 23 of the multigraph machine B. This crank arm 22 and shaft 23 are found on a known type of machine and are commonly utilized for operating the paper feed mechanism through a link 24. A collar 25 is slidably mounted on the rod 20 to engage the end of the bell-crank lever as shown in Figures 1 and 3, and a spring 26 is interposed between said collar and a sleeve 27 slidably on the rod but capable of being fixed thereto by means of a set screw 28. The extremity of the rod 20 is preferably provided with a cotter pin or the like 29 to prevent the rod from pulling out of the opening 18 in the bell-crank lever.

In the operation of the device, the body portion 1 is secured to the table A and the plate 7 is secured to the sideboard C, as shown. The sideboard C may then be adjusted relatively to the board D by manually sliding the rod 6 to move the plate 7 toward or away from the outer bearing post 5 against the influence of the spring 9. While the rod is so held, the sleeve 13 is adjusted on the rod to bring it substantially into engagement with the forked end 17 of the bell-crank lever, whereby the board C is held in the adjusted position by the sleeve 13 and set screw 14. The rod 20 is then connected at 21 to the crank arm 22 and the sleeve 27 adjusted so as to cause engagement of the collar 25 with the end of the bell-crank lever. The machine B is then started in operation and upon each revolu-

tion of the crank arm 22, the board C is moved through longitudinal movement of the rod 20, oscillation of the bell-crank lever 15 and sliding of the rod 6, toward the board D, as shown in dotted lines in Figure 2, as to 70 push the sheet against the board D. The movement of the board C toward the board D must be properly related to the discharge of each sheet of paper, that is the board C must move toward the board D after each 75 sheet has been discharged from the machine and moved away from the board D before the next sheet is discharged. In the arrangement shown, this synchronism is obtained through the crank arm 22 which has 80 a certain relation to the paper feed mechanism of the machine B. It will thus be observed that the board C is automatically operated to produce even stacking of the sheets of paper on the table A, the board C 85 being moved in one direction by power from the machine B and in the other direction by the spring 9. The spring 26 enables a certain relative movement of the rod 20 and the bell-crank lever 15 to prevent excessive 90 pressure of the board C against the stack of paper, at the same time producing the necessary yielding pressure against the stack.

It should be noted that the sleeve 13 enables adjustment of the rod 6 and the sideboard C in the direction of movement of the rod 6 toward or from the board D, relatively to and independently of the bell-crank lever 15. This is particularly important since it enables easy and quick adjustment of the jogger to use with paper of a certain width and permits adjustment of the movable sideboard C to correspond with the particular point of discharge of the sheets from the machine. The device is 100 usually adjusted by running a sheet nearly through the machine and arranging the stationary sideboard D about three quarters of an inch from the corresponding edge of the sheet. The sideboard C is then moved toward the board D by sliding rod 6 to push the sheet against the board D, whereupon the sleeve 13 is set against the outer bearing post 5 and the screw 14 tightened. The collar 25, spring 26 and sleeve 27 enable adjustment of the connection of the rod 20 to the bell-crank to accommodate different machines and also to accommodate sheets of paper of different widths in the same stack such as might occur from variations in the 110 cutting of different lots of paper.

While I have shown and described the invention in connection with a power operated multigraph machine, it will be understood that the jogger may be used in connection 115 with other types of machines and hand-operated machines without material modification of the structure of the jogger or the machine. Therefore I do not desire to be understood as limiting myself in the con- 120

struction and use of the invention except as may be required by the following claims when construed in the light of the prior art.

5 Having thus described the invention, what I claim is:

1. A device of the character described including a body portion to be secured to a paper stacking table, a member reciprocably mounted on said body portion to be connected to a sideboard of said paper stacking table, a bell-crank lever pivoted on said body portion with one arm operatively connected to said member to reciprocate the latter upon oscillation of said lever, a link having one end connected to the other arm of said bell-crank lever for longitudinal and pivotal movement and the other end formed to connect with a drive mechanism, and a spring for limiting longitudinal movement of said link in one direction.

2. A device of the character described including a body portion to be secured to a paper stacking table, a member reciprocably mounted on said body portion to be connected to a sideboard of said paper stacking table, a bell-crank lever pivoted on said body portion with one arm operatively and adjustably connected to said member to reciprocate the latter upon oscillation of said lever and permit longitudinal adjustment of said rod relatively to said bell-crank lever, a link having one end connected to the other arm of said bell-crank lever for longitudinal and pivotal movement and the other end formed to connect with a drive mechanism, and a spring for limiting longitudinal movement of said link in one direction.

3. A device of the character described including a body portion to be secured to a paper stacking table, a member reciprocable on said body portion to be connected to a sideboard of said paper stacking table, motion translating and power transmitting means to be connected to a source of power for reciprocating said member, and means for adjustably connecting said motion translating and power transmitting means to said member to permit adjustment of said member in the direction of its movement independently of said motion translating and power transmitting means.

4. A device of the character described including a body portion to be secured to a paper stacking table, a member reciprocable on said body portion to be connected to a sideboard of said paper stacking table, a tension spring for moving said member in one direction, a bell-crank lever pivoted on said body portion with one arm connected to said member to move the latter in the other direction upon swinging of said bell-crank lever in one direction, and a rod having one end connected to the

other arm of said bell-crank lever and the other end formed with an opening to receive a bolt.

5. A device of the character described including a body portion to be secured to a paper stacking table, a member reciprocable on said body portion to be connected to a sideboard of said paper stacking table, a tension spring for moving said member in one direction, an element adjustable on said member in the direction of movement thereof, a bell-crank lever pivoted on said body portion with one arm engaging behind said element to move said member in the other direction upon movement of said lever in one direction, and a rod having one end connected to the other arm of said bell-crank lever and the other end formed with an opening to receive a bolt.

6. A device of the character described including a body portion to be secured to a paper stacking table, a rod reciprocable on said body portion to be connected to a sideboard of said paper stacking table, a spring for moving said rod in one direction, a sleeve adjustable longitudinally of said rod, a bell-crank lever pivoted on said body portion and having one arm bifurcated to embrace said rod and engage behind said sleeve to move said rod in the other direction upon movement of said lever in one direction, and a second rod having one end connected to the other arm of said bell-crank lever and the other end formed with an opening to receive a bolt.

7. A device of the character described including a body portion to be secured to a paper stacking table, a rod reciprocable on said body portion to be connected to a sideboard of said paper stacking table, a spring for moving said rod in one direction, a sleeve adjustable longitudinally of said rod, a bell-crank lever pivoted on said body portion and having one arm bifurcated to embrace said rod and engage behind said sleeve to move said rod in the other direction upon movement of said lever in one direction, the other arm of said lever having a transverse opening, a second rod slidable in said opening and having one end provided with an opening to receive a bolt, a collar slidable on said rod to engage said arm of the bell-crank lever, a sleeve fixed on said rod, and a spring interposed between said collar and said sleeve.

8. The device set forth in claim 4 in which said reciprocable member is adjustable in the direction of its movement relatively to said bell-crank lever.

9. A device of the character described including a body portion to be secured to a paper stacking table, a member reciprocable on said body portion to be connected to a sideboard of said paper stacking table, a tension spring for moving said

member in one direction, an element adjustable on said member in the direction of movement thereof, a bell-crank lever pivoted on said body portion with one arm engaging behind said element to move said member in the other direction upon movement of said lever in one direction, the other arm of said lever having a transverse

opening, a second rod slidable in said opening and having one end provided with an opening to receive a bolt, a collar slidable on said rod to engage said arm of the bell-crank lever, a sleeve fixed on said rod, and a spring interposed between said collar and said sleeve.

JAMES A. CARLTON.
